Primary Examiner — Derrick Holland*Assistant Examiner* — Lauren Calve(74) *Attorney, Agent, or Firm* — Tucker Ellis LLP(57) **CLAIM**

The ornamental design for a merchandizing hanger, as shown and described.

DESCRIPTION

FIG. 1 is a front perspective view of a merchandizing hanger showing our new design;

FIG. 2 is another front perspective view thereof;

FIG. 3 is a rear perspective view thereof;

FIG. 4 is another rear perspective view thereof;

FIG. 5 is front view thereof;

FIG. 6 is a rear view thereof;

FIG. 7 is a top view thereof;

FIG. 8 is a bottom view thereof;

FIG. 9 is a left side view thereof; and,

FIG. 10 is a right side view thereof.

The broken lines shown represent unclaimed subject matter and form no part of the claimed design.
